(57) **CLAIM**

The ornamental design for a combination bookmark holder, as shown and described.

DESCRIPTION

FIG. 1 is a top perspective view of a combination bookmark holder, showing my new design;

FIG. 2 is a bottom perspective view thereof;

FIG. 3 is an exploded front elevational view thereof, the rear elevational view being a mirror image thereof;

FIG. 4 is a left-side elevational view of FIG. 2, the right-side elevational view being a mirror image thereof;

FIG. 5 is a top plan view of FIG. 2; and,

FIG. 6 is a bottom plan view of FIG. 2.

The broken lines are directed to environment and form no part of the claimed design.
